CHARGE FORMING DEVICE

Bob Drysdale, Sunnyvale, Calif.

Application May 6, 1944, Serial No. 534,478

6 Claims. (Cl. 123—127)

This invention relates to the fueling of internal combustion motors, and more especially to a method and means for operating gasoline engines with Diesel or fuel oil.

An object of the invention is to provide a method and means for operating the ordinary gasoline-driven motor of automobiles, trucks, tractors, marine engines, and the like, with inexpensive non-rationed Diesel or fuel oil, in lieu of gasoline.

Another object is to provide such a means which is readily adaptable to convert existing power units now running on gasoline or other relatively-expensive fuel, to operate satisfactorily with cheap Diesel or fuel oil.

A further object is to accomplish the above without material change to the gasoline carburetor or other essential operating parts of existing assemblies, to so make the invention easily installable as an attachment.

Yet another object is to provide such a method and means for this purpose, which will not lessen and will preferably increase the power of the motor by substitution of the heavier crude oil, will give equal or better performance, for instance, as regards rapid pick-up of speed, ability to climb hills or drag heavy trailers or other loads, and which will not foul the spark plugs with carbon deposit, or the valves or cylinders, and which will not substantially increase smoking from the exhaust.

Finally, an object is to accomplish all such purposes by a means employing simple cheap parts which are easily made and quickly installed by the ordinary mechanic, which have a long life, need little or no adjustment or maintenance, and which may be designed in a few sizes to accommodate many different conditions and motor sizes and arrangements.

All these and other objects as suggested herebelow, are attained by the method and means now to be described, and illustrated in the accompanying drawing, in which—

Figure 1 is a top plan view, largely in outline, showing the heat-enclosing containers over carburetor and manifold attached to the side of the engine block of an ordinary gasoline engine, and which containers comprise an essential element of this invention.

Fig. 2 is a side perspective view of the containers of Fig. 1, and attendant parts, as normally installed on a motor to enclose both its carburetor and manifold.

Fig. 3 is a partial side perspective view of Fig. 2, somewhat enlarged thereover, and with the

front of the containers removed to show the invention applied to the essential operating parts therein.

Fig. 4 is a cross-sectional view of the warm-air pipe leading from the manifold to the carburetor, and showing positioned therein the reducer plate for limiting the amount of warm air to the carburetor, to aid its successful functioning on the heavier fuel.

10 Fig. 5 is a side sectional detail view of the needle valve in the auxiliary, or gasoline starting, fuel line, and which is operable by remote control from the dashboard, if installed in a motor car.

15 And Fig. 6 is a top plan view, showing the hinged doors to regulate the cold air entering the front of the manifold container or chamber, with operating leverage for opening or closing them in opposite directions, in order to center 20 the air-flow.

Like numerals refer to like parts throughout the several views.

This drawing was made from photos of a typical installation of the invention as applied to 25 a Chevrolet car of a somewhat older model, after it had been in constant use thereon for a mileage equivalent of some two years' driving; it was still in perfect running order, and had never required any attention. With ordinary Diesel 30 oil, at about 6¢ a gallon, it made 20 miles on a gallon, compared to about 17 miles when the car (sans invention) used gasoline. And gasoline cost 2½ times more, and was war-rationed. The car started as readily, picked up as fast, 35 climbed or dragged a load as well, sooted the motor parts no more, and smoked no more than when operated solely on gasoline. Other installations, made on other cars and motors, worked as well.

40 In Fig. 1 is shown, in outline, the top of a gasoline motor 10, the container 11 which fairly-closely encloses its carburetor, and the container 12 which fits around the engine manifolds. Container 12 is preferably open on the side adjacent the motor, its edges being substantially in contact therewith. The Diesel or fuel oil line 14 is shown here entering the top of container 12, going down through it, and coming into container 11 to its carburetor from below. There is 45 also shown an inlet pipe 13 for gasoline, fed to the carburetor for starting, as explained below, and coming from a small tank of a quart or more capacity, preferably, which tank may be located 50 conveniently in the car's trunk, under the dash,

55

or at other convenient place relative to the motor.

In Fig. 2 is shown the water hose connection 15 to the radiator in front, from the motor block 10; also one type of door 16 hinged to swing open and closed over the front open end of container 12, to regulate the amount of cold air blown by the movement of the car, etc., into manifold container 12; also a linkage connection 17 connecting said door with a manual operating knob 19 extending through the dashboard 18 for convenient operation by the driver. Door 16 may also be operated automatically by means of a heat-controlled thermostat 20, either alone, or in combination with said manual control. The details of such thermostats for effecting movement by heat changes are well known by those skilled in the art, and hence the details are omitted. In stationary installations, cold air could enter through the front of the manifold with the aid of a driven fan, alone.

In Fig. 3, the edge of the top member of container 11 is indicated by the line 11a, the front 11b has been bent back to the left to show the carburetor and parts within, the front side is 11c, the back is 11d, the rear wall is shown in Fig. 2 at 11e, and the open bottom is attached, as by flanges, to top member 12a of manifold container 12, the front wall of which has been removed to show the parts within.

The standard gasoline carburetor is shown at 21. The air cleaner, normally attached to its top opening or air inlet, is first removed, and an air inlet pipe 22, which may be made of sheet metal, connects manifold container 12, through its top 12a, to the top of carburetor 21. The auxiliary gasoline line 13 is tapped into the carburetor, as shown, at a point below, or toward the motor, from its butterfly valve 21a, this being important. The drawing shows the carburetor wall broken away at this point to show this needed relation of valve and gas inlet. Pipe 13 leads to the auxiliary gasoline or starting tank, and admission of gasoline for starting the cold motor is effected by means of a conventional needle valve 24, Fig. 5, in gas line 13, operated by the standard choke wire 23 and pull-out knob 24 extending through dash 18. Thus the operator uses the normal choke knob in the usual way for starting, but the choke being no longer needed or connected, he instead introduces a little starting gasoline direct to the motor fuel intake manifold.

Since the normal air cleaner has thus been omitted, it may be desirable to provide a cleaner 25, Fig. 2, shown dotted, near the front end of manifold container or heat chamber 12, inside door 16. Or some other positioning of it might prove more desirable, in some instances.

It will be noted that the Diesel or main fuel oil line 14, Fig. 3, is led through chamber 12 to thus warm the oil, normally, before entering the carburetor.

Pipe 22 is pierced near its upper end by two diametrically-positioned slots, and lugs 26a of a reducer plate 26, Fig. 4, extend through these slots an equal distance, where they may be then bent over to hold plate 26 centrally in pipe 22. Thus, it will be noticed, plate 26 has a main central opening as well as side openings near the pipe wall. This permits the warm air to be fed directly to the centrally-positioned jet of the carburetor, as well as directly to the side-positioned jets, for most effective operation. The inner and other diameter of this plate, which may be formed of sheet metal, may be varied at will, until one size

has been found for best running conditions with a particular make of motor. It may also be adapted to the jet positions of different carburetors.

Container 12 closely encloses the manifolds of the motor, the exhaust manifold being shown at 21.

While in Fig. 2 one door 16 has been shown, for general illustration, to regulate the cold air intake to the heating chamber, a probably more effective arrangement is shown in top elevation in Fig. 6. Here there are two doors 28, 29 side-by-side, pivoting about central pins 28a, 29a top and bottom, with short keyed links 30, 31 extending oppositely at some 45 degrees thereto, their free ends pivotally connected by link 32, which in turn is connected to control rod 17, Fig. 2.

It will of course be understood that for adjusting the carburetor without removing container 11, either a door will be provided in the front wall, or at least a screw driver hole 33, Fig. 2.

The two container covers are preferably made of thin sheet iron, maybe 26 or 28 gauge, to permit warming up the air quickly without storing too much of the heat in said walls. The covers need not be tight.

Since there is a vacuum in the carburetor at the point where gasoline line 13 enters, the gasoline supply need not be positioned to be fed thereto by gravity.

With this invention installed on a standard automobile, the operation is as follows:

Put out the choke knob 24 (now gasoline). A teaspoonful or two of gasoline will flow through the base of the carburetor directly to the motor cylinders, by suction or gravity or both, when the starter is operated, and the motor will start. The spark plug points heat up, and will not thereafter foul. Now the gasoline is shut off by pushing back knob 24, and the motor continues to run on the Diesel or fuel oil which now fills the main (or old) gasoline tank; it not only runs on this fuel, but idles on it as well. When starting, door 16, Fig. 2 (or doors 28, 29, Fig. 6 as an alternate) are closed, either manually or thermostatically when the motor is cold. When the motor reaches normal temperature, as after traveling a mile or so, these doors, always slightly open, open or are opened fully.

There is never any danger of "flooding" the motor, because the former choke valve is now disconnected. And if you fail to return the gasoline knob 24 after starting, the motor will warn you by "loping," as it did formerly with the choke. Knob 19 is an extra, mounted on the dash 18 to operate by wire 17 the door or doors (16, or 28, 29) at the air entrance of manifold heat chamber 12. But by introducing thermostat 20, this part and its operation may be dispensed with.

The design of reducer plate 26, Fig. 4, not only prevents clogging, but effectively delivers air, warmed, to the high speed jet, normally in the center, and to the intermediate jets, placed along the carburetor wall.

The operating Diesel oil is not heated, but merely warmed by having its pipe pass through the chamber 12 which is warmed by the hot manifold exhaust pipe which it encloses. Only the air is heated in passing through this chamber, so there is entire absence of any danger.

Plate 26 serves to reduce the area of the air-inlet pipe to reduce the supply of warmed air going to the carburetor to thus enrich the mixture, needed with the lower-grade fuel, and also to speed up the flow of the heated air for bet-

ter combustion, and more rapid pick-up. No needle valve sizes or other changes are made to the standard carburetor, an important point.

The warmed air from chamber 12 is doubly insulated against heat loss both by pipe 22 and surrounding chamber 11. The fuel is mixed in the carburetor in this warm environment, and passes pre-heated to the motor in the form of an explosive mixture, to act as well as gasoline.

The invention costs little, and can be installed by any mechanic in about two hours. And a few sizes will fit all cars, etc.

Having now described the invention, what is claimed as new and for which Letters Patent of the United States is desired, is:

1. A means for operating a gasoline engine on fuel oil, including a heat-containing air chamber around the engine manifolds, another like-purpose chamber around the carburetor, a pipe connecting the chamber first-mentioned and the carburetor air intake to supply heated air thereto, and means for introducing raw gasoline direct to the inlet manifold of the engine for the purpose of starting only.

2. The invention as in claim 1, including remote control means for varying the amount of air entering the heat-containing chamber.

3. The invention as in claim 1, including thermostatically-controlled means for varying the amount of air entering the heat-containing chamber.

5. 4. The invention as in claim 1, including means in the air-intake to the carburetor for reducing the volume of air flowing, and increasing its speed of flow.

5. Means for converting a gasoline carburetor to one using fuel oil, including a pipe supplying heated air through the usual air cleaner opening, and means on said pipe for both reducing the amount of air passing through and also increasing its speed.

15. 6. In combination, means for introducing air around a heated exhaust manifold of an internal-combustion motor, means for regulating the amount introduced automatically and thermostatically by means of the heat of the motor, means for cleaning the cold air before heating it, means for passing the heated air to the carburetor of the motor, fuel oil feeding means to the carburetor for running, and gasoline feeding means to the carburetor-outlet for starting.

BOB DRYSDALE.
